US00D755756S

(12) **United States Design Patent**
Brunner et al.

(10) **Patent No.:** **US D755,756 S**
(45) **Date of Patent:** **** May 10, 2016**

(54) **AUDIO SPEAKER SYSTEM**

(71) Applicant: **Apple Inc.**, Cupertino, CA (US)

(72) Inventors: **Robert Brunner**, San Francisco, CA (US); **Eric Fields**, San Francisco, CA (US); **Martin Ruegg**, San Francisco, CA (US); **Sang Ik Lee**, Walnut Creek, CA (US)

(73) Assignee: **Apple Inc.**, Cupertino, CA (US)

(**) Term: **14 Years**

(21) Appl. No.: **29/493,772**

(22) Filed: **Jun. 12, 2014**

Related U.S. Application Data

(63) Continuation-in-part of application No. 29/441,336, filed on Jan. 3, 2013, now Pat. No. Des. 707,656.

(57) **CLAIM**

The ornamental design for an audio speaker system, as shown and described.

DESCRIPTION

FIG. 1 is a top perspective view an audio speaker system showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the audio speaker system that form no part of the claimed design.

1 Claim, 5 Drawing Sheets
